UNITED STATES PATENT OFFICE.

SETH WHEELER, OF CASTLETON, NEW YORK.

DISPENSING CABINET.

Application filed May 25, 1920. Serial No. 384,033.

To all whom it may concern:

Be it known that I, SETH WHEELER, a citizen of the United States, residing at Castleton, in the county of Rensselaer and State of New York, have invented a certain new and useful Dispensing Cabinet, of which the following is a specification.

My invention relates to dispensing cabinets and has for its object to provide a novel and efficient dispensing cabinet which may be coin-controlled if desired.

A further object of my invention is to provide a cabinet which will feed, among other articles or units, single or double sheets of paper either unfolded, or folded or inter-folded, in any desired manner.

A further object of my invention is to provide a cabinet which will feed only the desired unit and which will feed that unit positively and surely at one operation which may consist of a complete turn or turns of a feeding mechanism or only a portion of a complete turn or turns.

A further object of my invention is to provide a coin-controlled cabinet provided with a single operating means for both the coin-control mechanism and the feeding mechanism.

Other and further objects of my invention will be apparent from the following description and from the accompanying drawings illustrating one embodiment of my invention, in which—

Figure 1 is a front elevation of the cabinet;

Figure 2 a side elevation of the cabinet with the bottom broken away to show a portion of the feeding mechanism;

Figure 3 a general plan of the feeding rollers with adjacent parts in section;

Figure 4 a front elevation of the feeding rollers with adjacent parts in section;

Figures 5, 6, and 7 views of the gears, rollers, and guide disks, respectively, of one embodiment of the invention taken on the line 5, 6, and 7, respectively, of Figure 3 and looking in the direction of the arrows;

Figures 8, 9, and 10 views similar to Figures 5, 6, and 7 of another embodiment of the invention;

Figures 11, 12, and 13 views similar to Figures 5, 6, and 7 of another embodiment of the invention;

Figure 14 a vertical section taken sub-

stantially on the line 14—14 of Figure 15 looking in the direction of the arrows;

Figure 15 a vertical section taken substantially on the line 15—15 of Figure 14 looking in the direction of the arrows;

Figure 16 an enlarged vertical section of one embodiment of the feeding rollers showing an article to be dispensed in semi-dispensed position;

Figure 17 a detailed view (with adjacent parts in section and parts removed) of the coin-operating and locking devices showing the locking device in position to permit operation of the dispensing rollers;

Figure 18 a view of the upper part of Figure 17 showing the coin support when it is attempted to operate the cabinet without a coin in place;

Figure 19 a view of the upper part of Figure 17 showing the coin support in dumping position; and

Figure 20 an edge view of the coin support and associated parts in the position shown in Figure 18 (looking from the left of said figure and corresponding to Figure 14) and in exaggerated separation to show clearly the manner of association and support.

Similar reference characters refer to similar parts throughout the drawings.

In the embodiment of my invention chosen for purposes of illustration, the reference character 1 indicates a casing of any desired kind having a front cover 2 provided with flanges 3 adapted to extend over the casing. Cover 2 is provided with a coin slot 4, and with a peephole or sight 5 (preferably covered with glass) so that it can be ascertained readily when the cabinet should be refilled with the articles to be dispensed.

At the bottom of the casing is provided a plurality of delivery rollers adapted to feed the articles to be dispensed a sufficient distance to permit the articles to be grasped by the hand, and then preferably release the articles by moving the rollers apart so that the articles may be withdrawn from the cabinet. In the embodiment illustrated, the articles are interfolded towels with the inter-folds arranged in such a manner that when one unit is withdrawn from the cabinet a subsequent unit will be pulled into position to be engaged by the delivery rollers at the next operation thereof.

2

In the embodiment of the invention of Figures 5, 6, and 7 of the drawings, roller 7 of the coating rollers 7 and 8 is provided with a cutaway portion in order to release the articles to be dispensed after the cooperating circular portions of the rollers have advanced the articles the desired distance. Although only one cutaway portion is illustrated, it is obvious that a plurality of cutaway portions may be utilized on one or both of the rollers, the number depending upon the distance the roll is to be turned at each dispensing operation. The rollers are connected on one end by intermeshing gears 9 and 10, one of which as gear 9 preferably is provided with a raised portion 11 between any desired number of teeth (forming shallow teeth) to force the gears and therefore the rollers apart at the time the articles to be dispensed are to be released. The rollers are provided on the other end with guide disks 12 and 13, one of which as disk 12 preferably is provided with a hump 14 to assist in forcing the rollers apart at the same time this function is performed by the gears. In the embodiment illustrated, roller 7 is mounted in fixed bearings and roller 8 in spring-pressed bearings 15.

30 In the embodiment of the invention of Figures 8, 9, and 10 of the drawings, rollers 17 and 18 preferably are not provided with a cutaway portion or portions and gear 19 of intermeshing gears 19 and 20 is provided with a raised portion 21 of an extent sufficient to force the gears and therefore the rollers apart in order to release the articles to be dispensed. Guide disk 22 of the guide disks 22 and 23 at the other end of rollers 17 and 18 is provided with corresponding means 24 to separate that end of the rollers.

45 The embodiment of the invention of Figures 11, 12, and 13 of the drawings, is similar to the embodiment of Figures 5, 6, and 7 with the exception that roller 27 of rollers 27 and 28 is provided with means, as round-headed nails 35 or their equivalent, which prevent the withdrawal of the article to be dispensed before the separation of the rollers is at its maximum. Gear 29 of intermeshing gears 29 and 30 in this embodiment is provided with a raised portion 31 preferably of less extent than raised portion 11 of gear 9, and guide disk 32 of guide disks 32 and 33 is provided with a hump 34 preferably corresponding in extent to the raised portion 31 between the teeth of gear 29.

50 It is to be understood that the embodiments in Figures 5 to 13, inclusive, may be interchanged or modified as may be necessary or advisable.

55 The dispensing operation of the rollers is accomplished in the present embodiment through a one-way clutch, one member of which is connected to one of the rollers and the other member of which is connected to a flexible hand operating member. In this embodiment, one of the trunnions of one of the rollers, as trunnion 40 of roller 7 (Figure 14) is extended to form a bearing for the clutch. One clutch member 43 is shown as having connected therewith a sleeve 41 provided with a lifting cam 42 to operate the coin-lock device. This clutch member is mounted rotatably on trunnion 40 and its rotatable movement limited by a lock motion device as, for example, a pin 44 secured in trunnion 40 and engaging a slot 45 (Figure 17) in sleeve 41 of the clutch member. This pin and slot connection permits lifting cam 42 to operate the coin-lock device to release the dispensing rollers before any turning movement is imparted to them. A spring 47 (Figure 14), one end of which is secured to pin 44 on trunnion 40 and the end to clutch member 43 as by a screw 48, maintains sleeve 41 and its lifting cam 42 in proper position to utilize the pin and slot connection for the sequence of operation just mentioned.

60 Said clutch member 43 cooperates with a clutch member 50 having connected therewith a sheave 51 in which is secured a flexible operating member as a chain 52 having a stop 53 thereon engaging the entrance of the passageway in the cabinet for the chain, in order to limit upward movement of said chain and thus the rotation of sheave 51 induced by a conical volute spring 54, one end of which is secured to the sheave and the other end to a plate 55 secured in adjusted position in any desired manner as by having holes 56 therein engaged by a pin 57 mounted or otherwise secured to an immovable part as a bracket or frame piece 58. Spring 54 also tends to keep clutch members 43 and 50 in operative connection, the faces of said clutches being formed so that when chain 52 is pulled downward, the clutch faces will engage operatively to turn clutch member 43 and trunnion 40 through its pin and slot connection therewith, and when chain 52 is released the clutch faces will pass each other inoperatively until stop 53 on chain 52 engages the entrance of chain passageway 81 at which time clutch member 50 and chain 52 are in normal position ready for the next dispensing operation.

65 To adapt the delivery rollers for use in connection with a coin-lock device, a locking strip 60 (Figures 15 and 17) is provided in the embodiment illustrated, having an extension provided with a locking shoulder 61 and with a cam member 62. Said shoulder 61 is engaged by a cooperating shoulder connected with one of the dispensing rollers as a shoulder 63 on an extension of gear 9, and cam 62 is engaged by a cooperating cam 64 which also is shown in this embodiment as on said extension of gear 9. When

locking strip 60 is in normal position, the dispensing rollers cannot be turned as shoulder 63 on gear 9 engages locking shoulder 61 on locking strip 60. When locking strip 60 is raised by mechanism to be described hereinafter, locking shoulder 61 of the locking strip is removed from the path of shoulder 63 on gear 9 (Figure 17) and the dispensing rollers can be turned sufficiently to feed the article to be dispensed a sufficient distance to be grasped, at which time the cam 64 on gear 9 will have engaged cam member 62 on locking strip 60 and returned the strip to normal locking position with its locking shoulder 61 in the path of shoulder 63 on gear 9.

Locking strip 60 is operated in connection with a coin by an associated strip 70 adapted to be raised by cam 42 on sleeve 41 engaging any desired portion of said associated strip 70 as a projection 71 at the bottom thereof. The raising of associated strip 70 by cam 42 will not raise locking strip 60 unless a coin is in place between the two strips. The mechanism to support the coin between the strips long enough to connect the strips operatively consists in the present embodiment of a coin support 72 pivoted to associated strip 70 and having a slot 73 engaged by a pin 65 on locking strip 60. An abutment 66 also is provided on locking strip 60 a sufficient distance above coin support 72 to receive a coin of the desired denomination therebetween. It is evident that if associated strip 70 is raised without a coin in place, it will not affect locking strip 70. Coin support 72 will assume the position shown in Figure 18. When a coin is in place, however, the raising of associated strip 70 will lift the coin (supported by coin support 72) against abutment 66 on locking strip 60, raising it to unlocking position in which its locking shoulder 61 will be removed from the path of shoulder 63 of roller 7. As soon as lifting cam 42 has passed projection 71 of associated strip 70, a spring 74 connecting strip 70 with the frame will return strip 70 to lowered position while locking strip 60 still is maintained in upward position by cam 64 engaging the portion of strip 60 below its shoulder 61. This relative movement of strip 70 causes coin support 72 to assume the position shown in Figure 19 thus dumping the coin from the support and preventing its use again to operate the locking device by pulling operating chain 52 very quickly and before the coin has had an opportunity to fall. A spring 67 also may connect locking strip 60 to the frame to ensure its following cam surface 64 before said cam reaches cam member 62 thereon.

In order to assist an even distribution of the articles to be dispensed, friction waves 80 may be provided inside the cabinet and the delivery opening 81 may be provided ad-

jacent its top with a projection 82 preferably of circular or rounding formation.

The operation of the apparatus is as follows:

A coin inserted in coin slot 4 will fall to coin support 72 where it is supported, preferably on edge, between locking strip 60 and its associated strip 70. When operating chain 52 is pulled downward clutch member 50 will be rotated and by its operative engagement with clutch member 43 will cause the rotation of said clutch member 43 and its associated sleeve 41 and lifting cam 42 which engages and lifts projection 71 on associated strip 70. As the coin is supported by coin support 72 on associated strip 70, the coin will be lifted, and as the coin is in engagement with abutment 66 on locking strip 60, the locking strip likewise will be lifted, removing its locking shoulder 61 from the path of movement of shoulder 63 connected with roller 7. If a coin is not in place on coin support 72 the operation of operating chain 52 will tend only to raise associated strip 70 without moving locking strip 60 so that shoulder 63 associated with roller 7 remains in place in the path of locking shoulder 61 on locking strip 60 thus preventing rotation of roller 7 and the feeding of the articles to be dispensed.

After associated strip 70 has been lifted by lifting cam 42 and locking strip 60 has been lifted by the coin between strips 60 and 70 as set forth above, so that roller 7 is free to rotate, the continued downward operation of operating chain 52 will cause pin 44 in trunnion 40 of roller 7 to be engaged by the end of slot 45 in sleeve 41 and thus rotate roller 7. As rollers 7 and 8 are geared together, both rollers will rotate to feed the articles to be dispensed a sufficient distance to permit a unit to be grasped. At this time the cutaway portion on roller 7 (or roller 27) will come opposite its associated roller 8 (or 28) and permit the articles to be pulled from the cabinet, the present embodiment showing the articles as paper towels so interfolded that when one unit (consisting of one or more towels) is withdrawn from the cabinet, the end of a succeeding unit will be drawn into position between the rollers. The release of the articles from the rollers is assisted or accomplished, as the case may be, by the raised portion 11 between the teeth of gear 9 (Figure 5) and hump 14 on guide disk 12 (Figure 7), forcing gear 10 and guide disk 13 away from gear 9 and guide disk 12, respectively, which is permitted by the spring-pressed bearings 15 (Figure 3) for roller 8, thus forcing apart the rollers 7 and 8. The raised portion 21 of gear 19 (Figure 8) and the hump 24 of guide disk 22 (Figure 10), and also the raised portion 31 of gear 29 (Figure 11) and the hump 34 of guide disk 32 (Figure 13),

act in a similar manner to raised portion 11 of gear 10 (Figure 5) and hump 14 of guide disk 13 (Figure 7), to force apart the rollers in these embodiments.

5 In the present construction, therefore, by one movement of the operating chain 52 the coin-lock device functions as set forth above and feeds the articles to be dispensed when a coin is in place and prevents feeding when 10 a coin is not in place.

Many modifications of my invention will be apparent to those skilled in the art without departing therefrom or from the scope of the claims, my invention not being limited 15 to the particular embodiment chosen to illustrate the same but comprising a dispensing cabinet, adapted if desired to use a coin-lock device, from which articles are dispensed by one operation of the operating 20 device.

What I claim and desire to protect by Letters Patent is:

1. In a vending cabinet, a casing, means to maintain articles therein, and means to 25 deliver said articles from said casing comprising a plurality of rollers provided with means to force said rollers apart at a pre-determined delivery time.

2. In a vending cabinet, a casing, means 30 to maintain articles therein, means to deliver said articles from said casing comprising a plurality of spring-pressed rollers and means for forcing said rollers apart at the time of delivery.

3. In a vending cabinet, a casing, means 35 to maintain articles therein, and means to deliver said articles from said casing comprising a plurality of rollers provided with gears one of which has means to force said 40 rollers apart.

4. In a vending cabinet, a casing, means to maintain articles therein, and means to deliver said articles from said casing comprising a plurality of rollers provided with 45 gears one of which has shallow teeth to force said rollers apart.

5. In a vending cabinet, a casing, means to maintain articles therein, and means to deliver said articles from said casing comprising a plurality of rollers provided with 50 guide disks one of which has means to force said rollers apart at the time of delivery.

6. In a vending cabinet, a casing, means to maintain articles therein, and means to deliver said articles from said casing comprising a plurality of rollers provided with 55 guide disks one of which has a hump to force said rollers apart at the time of delivery.

7. In a vending cabinet, a casing, means 60 to maintain articles therein, and means to deliver said articles from said casing comprising a plurality of rollers provided with gears and with guide disks having means to force said rollers apart at the time of 65 delivery.

8. In a vending cabinet, a casing, means to maintain articles therein, and means to deliver said articles from said casing comprising a plurality of rollers provided with 70 gears one of which has shallow teeth and with guide disks one of which has a hump to force said rollers apart.

9. In a vending cabinet, a casing, means to maintain articles therein, and means to deliver said articles from said casing comprising a feeding means, a clutch one member of which is connected to said feeding means, an operating device connected to the other member of said clutch, and a spring to move the clutch member connected to said 80 operating device angularly to normal position after its operation by said operating device.

10. In a vending cabinet, a casing, means to maintain articles therein, and means to deliver said articles from said casing comprising a feeding means, a clutch one member of which is connected to said feeding means, an operating device connected to the other member of said clutch, and a spring 90 to return the clutch member connected to said operating device to normal position after its operation by said operating device, said spring urging said clutch members into 95 operative contact.

11. In a vending cabinet, a casing, means to maintain articles therein, and means to deliver said articles from said casing comprising a feeding means, a locking device for said feeding means, a clutch one member of which is connected to an operating device and the other member of which has associated therewith means adapted to operate said locking device, and means to connect said last named clutch member to said 100 feeding means so that said locking device will be operated before said feeding means is operated.

12. In a vending cabinet, a casing, means to maintain articles therein, and means to deliver said articles from said casing, comprising a feeding means, a locking device for said feeding means, a clutch one member of which is connected to an operating device and the other member of which has associated therewith means adapted to operate said locking device, and means to connect said last named clutch member to said 110 feeding means comprising a pin and slot connection adapted to permit the operation 115 of said locking device before the operation of said feeding means.

13. In a vending cabinet, a casing, means to maintain articles therein, and means to deliver said articles from said casing comprising a feeding means, a locking device for said feeding means, a clutch one member of which is connected to an operating device and the other member of which has 120 means adapted to operate said locking de- 125

- vice, means to connect said last named clutch member to said feeding means so that said locking device will be operated before said feeding means is operated, and means 5 normally adapted to maintain said last named clutch member in position to cause said delayed operation.
14. In a vending cabinet, a casing, means to maintain articles therein, and means to deliver said articles from said casing comprising a feeding means, a locking device for said feeding means, a clutch one member of which is connected to an operating device and the other member of which has 10 associated therewith means adapted to operate said locking device, means to connect said last named clutch member to said feeding means so that said locking device will be operated before said feeding means is operated, and a spring normally adapted to 15 maintain said last named clutch member in position to cause said delayed operation.
15. In a vending cabinet, a casing, means to maintain articles therein, means to deliver said articles from said casing comprising an operating device, and means to lock said delivery means comprising a vertically movable locking strip, an associated vertically movable strip adapted to be operated by said operating device, and means 20 to support a coin between said strips to connect them operatively.
16. In a vending cabinet, a casing, means to maintain articles therein, means to deliver said articles from said casing comprising an operating device, and means to lock said delivery means comprising a locking strip, an associated strip adapted to be operated by said operating device, and 25 means to support a coin between said strips to connect them operatively comprising a coin support pivoted to said associated strip.
17. In a vending cabinet, a casing, means to maintain articles therein, means to deliver said articles from said casing comprising an operating device, and means to lock said delivery means comprising a locking strip, an associated strip adapted to be operated by said operating device, and 30 means to support a coin between said strips to connect them operatively comprising a coin support pivoted to said associated strip.
18. In a vending cabinet, a casing, means to maintain articles therein, means to deliver said articles from said casing comprising an operating device, and means to lock said delivery means comprising a vertically movable locking strip, an associated vertically movable strip adapted to be operated by said operating device, and means 35 to support a coin between said strips to connect them operatively comprising a coin support on said associated strip and a stop 65 on said locking strip above said support a sufficient distance to be engaged by a coin when said associated strip is raised.
19. In a vending cabinet, a casing, means to maintain articles therein, means to deliver said articles from said casing comprising an operating device, and means to lock said delivery means comprising a vertically movable locking strip, an associated vertically movable strip adapted to be operated by said operating device, and means to return said strips to normal position 70 after the operation thereof.
20. In a vending cabinet, a casing, means to maintain articles therein, means to deliver said articles from said casing comprising an operating device, and means to lock said delivery means comprising a vertically movable locking strip, an associated vertically movable strip adapted to be operated by said operating device, and means to return said strips to normal position 75 after the operation thereof comprising springs.
21. In a vending cabinet, a casing, means to maintain articles therein, means to deliver said articles from said casing comprising an operating device, and means to lock said delivery means comprising a vertically movable locking strip, an associated vertically movable strip adapted to be operated by said operating device, a coin support operatively connected between said strips, means to maintain said locking strip 80 in operated position, and means to return said associated strip to normal position after operation while said locking strip is maintained in operated position.
22. In a vending cabinet, the combination of means for maintaining a stack of interfolded paper units, means for advancing the lowermost unit to a position in which it may be grasped and for then releasing said unit while still leaving it interfolded with the next successive unit, coin-controlled means to lock said delivery means, and a single operating device adapted to operate said coin-controlled means and to operate said delivery means at one operation. 105
23. In a vending cabinet, the combination of means for maintaining a stack of interfolded paper units, rollers for advancing the lowermost unit to a position in which it may be grasped while leaving it still interfolded with the next successive unit, means to then release the grip of said rollers on said unit, coin controlled means to lock said rollers, and a single operating device adapted at one operation to unlock said locking means and to operate said rollers. 110
24. In a vending cabinet, the combination of means for maintaining a stack of inter-

folded paper units, rollers for advancing the lowermost unit to a position in which it may be grasped while leaving it still interfolded with the next successive unit, means to then separate said rollers so as to release said unit from their grip, coin controlled means to lock said rollers, and a

single operating device adapted at one operation to unlock said locking means and to operate said rollers in the order named. 10

In testimony that I claim the foregoing, I have hereunto set my hand this 22nd day of April, 1920.

SETH WHEELER.

Certificate of Correction.

It is hereby certified that in Letters Patent No. 1,457,333, granted June 5, 1923, upon the application of Seth Wheeler, of Castleton, New York, for an improvement in "Dispensing Cabinets," errors appear in the printed specification requiring correction as follows: Page 2, line 85, after the article "the" insert the word *other*; page 4, line 129, claim 13, after the word "has" insert the words *associated therewith*; and that the said Letters Patent should be read with these corrections therein that the same may conform to the record of the case in the Patent Office.

Signed and sealed this 26th day of June, A. D., 1923.

[seal.]

KARL FENNING,
Acting Commissioner of Patents.
